(57) **CLAIM**

The ornamental design for a transparent crystal yoyo ball, as shown and described.

DESCRIPTION

FIG. 1 is a perspective view of the transparent crystal yoyo ball showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view similar to FIG. 1 but showing the interior floating glitter particles in a suspended state within the liquid filled interior;

FIG. 9 is a perspective view similar to FIG. 8 but showing an alternate embodiment in which the interior floating glitter particles are star shaped; and,

FIG. 10 is a cross sectional view taken along line 10-10 of FIG. 6, except for the full view of the screw element.

The broken lines in FIGS. 8 & 9 are included for the purpose of illustrating the cord portion of the transparent crystal yoyo ball that forms no part of the claimed design.
